UNITED STATES PATENT OFFICE.

SAMUEL A. NORSTROM, OF CHICAGO, ILLINOIS, ASSIGNOR TO CASPER L. REDFIELD, OF CHICAGO, ILLINOIS.

TELEPHONE-EXCHANGE.

No. 871,043.

Specification of Letters Patent.

Patented Nov. 12, 1907.

Application filed August 23, 1905. Serial No. 275,340.

To all whom it may concern:

Be it known that I, SAMUEL A. NORSTROM, a citizen of the United States of America, and a resident of Chicago, county of Cook, and State of Illinois, 5 have invented certain new and useful Improvements in Telephone-Exchanges, of which the following is a specification.

My invention relates to telephone exchanges of the party line type and has for its object improvement in 10 the arrangement and operation of such exchanges.

In party line exchanges of the present kind there is a central office from a spring jack in which extend two wires. A series of local stations are connected by branch wires to these main wires. At each local station 15 there is a switching mechanism the most prominent elements of which are a ratchet wheel, and a magnet and pawl for driving it. The ratchet wheel is advanced from its normal position by the action of the magnet and the driving pawl, and when released 20 it returns to its normal position by spring action.

The ratchet wheel has one tooth removed, and, when the wheel is in its normal position, this vacant place in the wheel is about twelve steps away from the ordinary holding pawl for a ten-station exchange, 25 or twenty-two or twenty-three steps for a twenty-station exchange.

There is one ordinary holding pawl and one special holding pawl. The latter comes into operation when desired for the purpose of enabling the driving pawl 30 to advance the wheel far enough for the vacant tooth to pass the ordinary holding pawl. The special holding pawl has a pin which engages a slot in a balance wheel. This wheel has a projection which, when the switching mechanism is not in operation, rests against 35 the driving pawl or the lever which operates it. In this position the slot for the pin in the special pawl enables that pawl to engage the teeth of the ratchet wheel. When the driving pawl moves to advance the ratchet wheel, the balance wheel follows it for a short 40 distance, the slot in the wheel moving on the pin in the pawl. When the driving pawl is retracted preparatory to again advancing the ratchet wheel, it strikes the projection on the balance wheel and drives it in the opposite direction far enough to cause the 45 slot engaging the pin to lift the special pawl clear of the ratchet wheel, which is the condition at the next forward movement of the driving pawl. The weight of the balance wheel and the force applied for moving its projection in the direction of the driving pawl are 50 so related to the speed with which that pawl is normally operated that the said balance wheel is inward and has its projection ready to be struck and forced outward each time that the driving pawl is retracted. The result is that while the special pawl engages the

ratchet wheel after each forward movement, it is not 55 in operative engagement at the beginning of such movement.

On the balance wheel is a pin and on the ratchet wheel is an adjustable sector having a flange adapted to engage said pin. If the driving pawl moves uniformly and continues to deliver blows upon the projection on the balance wheel, the flange engages the pin in such a way as to hold the special pawl from engagement with the ratchet wheel, with the result that the ratchet wheel must stop when the blank part 65 reaches the ordinary holding pawl. If the driving pawl pauses in its normal position, then the special pawl rests against the ratchet wheel and the flange engages the pin so as to keep the special pawl in operative engagement. In this case the special pawl 70 acts as a holding pawl and the driving pawl can move the blank part of the ratchet wheel past the regular holding pawl.

In the accompanying drawings, Figure 1 is an elevation of the switching mechanism with the front 75 plate removed; Fig. 2 is a section on line 2—2 of Fig. 1; Fig. 3 is a section through the ratchet wheel and its adjustable sector. Fig. 4 is a plan of the clamping bar by means of which the spools of the magnet are vertically adjustable; and Fig. 5 is a diagram showing 80 two local stations on a line together with a part of the central office at the extreme left.

In Fig. 1 all of the pawls and the balance wheel are represented as being actuated by gravity, though they may be actuated by springs if so desired. The 85 operating magnet A—A¹ is held between the plates P and P¹, as is also the rest of the switching mechanism. The armature A² is pivoted at A³ and is provided with a driving pawl A⁵ which engages the teeth of the ratchet wheel B, which wheel is secured to a 90 pivoted spindle B². The spools A and A¹ of the magnet are polarized and have their projecting cores supported in a clamping bar A⁶. By this means the spools are independently adjustable so as to properly limit the armature movement. The ratchet wheel 95 B has one tooth removed as shown at B³. In a ten-station exchange the space or blank part B³ would be twelve steps away from the holding pawl B⁴ when the ratchet wheel is in its normal position.

Fig. 1 shows the driving pawl A⁵ as located between 100 the blank space B³ and the holding pawl B⁴. To enable the driving pawl to operate past this blank space it is provided with two teeth. If the holding pawl is located between the blank space and the driving pawl, then the driving pawl needs but one tooth. 105 On the face of the ratchet wheel B is a sector O having a flange O¹ and two spring prongs O² which embrace the spindle B². The ends of these prongs are bent

in and are adapted to enter a groove B^1 in the wheel B . A nut O^3 clamps the sector O in position, or it may be held in position by the spring action of the prongs between the wheel B and a fixed collar where the nut O^3 is located. As thus made the sector may be readily removed and is adjustable to any desired position with respect to the blank space in the wheel B . Pivoted at C^1 are a special pawl C and a balance wheel D . The pawl C falls by gravity into the teeth 10 of the wheel B , and the balance wheel D has part of the upper portion cut away so as to make it lighter than the lower portion. The remaining weight of the balance wheel D is so distributed as to tend to fall in the same direction that the special pawl C falls. This 15 movement is stopped by a projection or lug D^2 striking and resting against the back of the driving pawl A^5 when said pawl is in its normal position. When the driving pawl A^5 is moved from its normal position to advance the ratchet wheel B , the upper part of the 20 balance wheel follows this movement until the projection D^2 rests against a stop pin D^3 . When the driving pawl A^5 returns to its normal position, it strikes the projection D^2 and drives the upper part of the balance wheel D in the opposite direction. 25 On the pawl C is a pin C^2 which engages a slot D^1 in the wheel D . When the parts are in their normal position the pin C^2 occupies about the position in the slot D^1 that is shown in Fig. 1. When the lug or projection D^2 is struck by the pawl A^5 in returning from a 30 ratchet wheel driving movement it forces the upper part of the balance wheel D to the right and this carries the pawl C with it so as to clear the teeth of the ratchet wheel B . The weight of the balance wheel D and of the pawl C are such that their return movement 35 toward the ratchet wheel B is sluggish. This is to prevent the special pawl C from engaging the teeth of the ratchet wheel B until the driving pawl A^5 has started to return after a driving operation. This movement, however, is not so sluggish as to prevent the lug D^2 40 from arriving at a position to be struck as before described.

On the balance wheel D is a pin D^4 so located that when the balance wheel is in its normal position the distance of this pin from the center of the ratchet wheel B is slightly greater than the distance of the flange O^1 from the same center. The sector O being adjustable about this center, the forward edge of this flange may be normally at any desired distance from this pin. This distance varies for different stations on the party line. For the first station this distance is a trifle more than the space between one tooth and the next; for the second station it is a trifle more than the space for two teeth; and so on. If, when the forward edge of the flange O^1 is close to the pin D^4 , the ratchet wheel driving movement begins from a position of rest with the special pawl C in engagement with the teeth of the ratchet wheel, then the flange O^1 will pass inside of the pin D^4 and the return blow of the pawl A^5 on the projection D^2 cannot drive the balance wheel D far 55 enough to lift the pawl C from the ratchet wheel B . In this position the driving pawl A^5 can drive the blank space B^3 past the pawl B^4 . If, however, the balance wheel D is driven outward by the pawl A^5 at the time this pawl begins to advance the ratchet 60 wheel B , then the flange O^1 will pass outside of the pin D^4

D^4 with the result that the pawl C will be held out of engagement with the ratchet wheel B . In this condition, the pawl A^5 cannot advance the blank space B^3 beyond the holding pawl B^4 .

Back of the ratchet wheel B are a series of contact 70 springs two of which, 3 and 13, are provided with cords E which extend to and wrap around the spindle B^2 . (See Fig. 5.) These cords are provided with suitable screws and adjusting nuts E^1 by means of which a tension from these springs is put upon the spindle B^2 . At 75 the first forward step of the ratchet wheel B the springs 3 and 13 are drawn inward and have their electrical connections broken with the springs immediately outside of them. If the ratchet wheel B does not advance far enough for the blank space B^3 to pass the holding 80 pawl B^4 , then the springs 3 and 13 are not moved far enough to connect to the adjacent inner springs. When the ratchet wheel is released the springs 3 and 13 act to return it to its normal position.

The propelling magnet A , A^1 is polarized so that 85 when a current flows through it in one direction it operates the pawl A^5 to advance the ratchet wheel B . When a current flows in the opposite direction it moves the pawl A^5 in the other direction and causes a release. In either case, after the current ceases the driving pawl 90 returns to its mid-position in the ordinary manner. When the pawl A^5 moves from its normal position in a direction opposite to that in which it drives the ratchet wheel, a small projection on the rear of the pawl A^5 strikes the pin D^3 and raises that pawl clear of the 95 ratchet wheel. The lever A^4 also pushes on the lug C^2 to move and raise the special pawl C . By a suitable connection A^7 from the lever A^4 to the pawl B^4 that pawl is also released by the same movement. When the driving pawl A^5 is at the extreme of its driving 100 movement, it comes into electrical connection with a stop screw F which is provided with a conductor extending through a condenser W to one branch of the party line. The pawl A^5 through the lever A^4 is provided with a conductor to the other branch so that the 105 final part of an advance movement bridges these two branches.

At each local station there is an ordinary telephone set including receiver R , hook H , generator G , a high-wound biased ringer Q which is simply an ordinary 110 polarized ringer with its armature held to one side by a spring so that it may be operated by a pulsating current, an emergency key L , and certain contact springs and connections as shown and as will appear from the description of the operation.

At the central office are a jack J , a plug P , a drop S , a battery X , keys M and N for sending impulses in opposite directions over the party line, and contacts and connections as shown. There is, of course, an ordinary telephone set provided with connections to the plug 120 but as they are unnecessary to an understanding of the invention they are not shown. The keys M and N are shown for operating the exchange to avoid the necessity of illustrating and explaining, in the present application, a fully organized calling device for sending the kind of impulse needed.

The two stations illustrated in Fig. 5 are marked No. 1 and No. 2, and, for the purposes of description, it will be assumed that the subscriber at station No. 1 wishes to talk to the subscriber at station No. 2. Upon turn- 130

ing the crank of his generator a current flows: G—1—2—3—4—5—6—7—8—9—S—10—11—12—13—14—15—16—17—G. This operates the drop S and calls the operator who inserts plug P in the jack J. Upon being informed in the ordinary manner that station No. 1 wants station No. 2, the operator presses key N a series of times. Upon the first contact a current flows: X—18—19—N—20—21—11—12 of each station—22—A, A¹—5—6—7—23—24—25—26—X. This advances all ratchet wheels one step each and brings the flanges O¹ on the sectors O one step nearer the pins D. Upon breaking this circuit the pawl A⁵ returns to normal position and drives the upper part of the balance wheel D outward so as to lift the special pawl C from the ratchet wheel, and also so as to bring the pin D⁴ inside of the line of movement of the flange O¹. If the second contact at key N immediately follows the first, then the second forward step of the ratchet wheel B at station No. 1 will cause the flange O¹ to pass outside of the pin D⁴ and, as a consequence, the special pawl C will be held away from the ratchet wheel during the remainder of the forward movement. But as station No. 1 is one of the two stations wanted, the operator pauses after making and breaking the first contact with key N for a time sufficient to permit the lug D² to settle back against the pawl A⁵. Then when she makes the second contact to again advance the ratchet wheels, the flange O¹ of station No. 1 passes inside of the pin D⁴ and the pawl A⁵ is thereafter prevented from driving the pawl C out of operative engagement with the ratchet wheel. As station No. 2 is also wanted she makes a similar pause after the second contact so that the flange O¹ of that station will come inside of the pin, but as other stations are not wanted she makes no similar pause after the other contacts. This causes the pins D⁴ of those stations to come inside of the flanges O¹. If the exchange is a ten-station one, then the blank spaces B³ come to the holding pawls B⁴ at the twelfth contact made by the operator and all of the ratchet wheels come to a stop at this point except the selected two which have their special pawls C in operative engagement with the ratchet wheels B. When the wheels have been advanced far enough for the blank spaces B³ to reach the holding pawl B⁴, the springs 3 and 13 have been moved inward far enough to connect to the adjacent springs 32 and 38. At the first step which carries the blank part B³ beyond the holding pawl B⁴, these springs are moved still further inward and close 38 to 37 and 28 to 29. When the ratchet wheels of selected stations reach this position, the extra resistance thrown upon the cords E by the additional springs serve to prevent further advance, or a permanent stop may be put behind the springs as shown at E³ in Fig. 5. When these springs are closed as described branches are provided for the impulses being sent from the central office as follows:—12—27—28—29—30—Q—31—52—H—1—32—3—4—etc. This calls the subscriber. With both receivers removed and beginning at station No. 1, the talking circuit is R—33—34—H—1—32—3—4—5—6—5 of No. 2—4—3—32—1—H—34—33—R—35—16—15—36—37—38—13—12—11—12 of No. 1—13—38—37—36—15—16—35—R. At each station is an emergency key L by pressing which a subscriber may connect his generator to, and call the central office over, a busy line. From the generator to the

line on one side the connection is:—G—1—32—3—4—5—6. On the other side it is:—G—17—16—35—40—41—42—38—13—12—11. This is made possible because at the stations not selected the blank part B³ is as far as the holding pawl B⁴, and in this position connections are closed to springs 32 and 38, although not to springs 29 and 37.

Referring to the original current for operating it will be seen that it goes through the line 12 and branches to 22 adjacent to the condenser W. This condenser stops the battery current used for operating the magnet but becomes charged by reason of that current. Also extending from the line 12, but on the opposite side of the condenser from the branch 22, is the branch 45 leading to the stop screw F.

As before described, when the magnet is actuated to advance the ratchet wheel, the driving pawl A⁵ makes electrical connection with the screw F at its extreme movement thus bridging lines 12 and 5 by way of 45—F—A⁵—A⁴—46. This contact between A⁵ and F exists at the time that the operator breaks the electrical connection by which she sent an operating impulse. At the instant she breaks the connection the condenser discharge of opposite polarity flows: W—12—22—A, A¹—5—46—A⁴—A⁵—F—45—12—W. The result of this is to destroy the residual magnetism in the magnet and prevent its armature from sticking. As there is a condenser of this kind at each station, and the connections through which the discharge occurs are of short lengths, the efficiency of the discharge is not dependent upon the length of the party line as would be the case with a condenser at the central office. The consequence is that the efficiency is the same at all stations.

What I claim is:—

1. The combination with a central office, a party line, and a series of local stations connected to the party line, of switching mechanisms at the stations adapted to be advanced by impulses sent from the central office, means by which all switching mechanisms automatically stop at the end of a predetermined number of steps, and means controlled from the central office for causing the switching mechanisms of selected stations to move beyond their normal stopping points.

2. The combination with a series of switching mechanisms located at a series of stations, and means for simultaneously advancing them, of means forming part of each switching mechanism by which all are automatically stopped at a predetermined point, and means controlled from a distance for causing selected switching mechanisms to move beyond their stopping points.

3. The combination with a switching mechanism adapted to be normally stopped at a predetermined point in its advance movement, and means for causing its advance beyond its normal stopping point, of a telephonic connection arranged to be closed by such extra movement.

4. The combination with a switching mechanism adapted to be normally stopped at a predetermined point in its advance movement, and means for causing it to advance beyond its normal stopping point, of an emergency signaling connection closed by the switching mechanism at its normal stopping point, and a telephonic connection closed by a movement beyond the normal stopping point.

5. In a switching mechanism, the combination with a ratchet wheel having one tooth removed, a driving pawl, and a holding pawl, of a special pawl normally out of engagement with said wheel while being advanced, and means for causing said special pawl to engage said wheel so that the driving pawl can advance the ratchet wheel with its toothless part beyond the holding pawl.

6. In a switching mechanism, the combination with a

- ratchet wheel and a driving pawl therefor, of a special pawl, and means controlled by the movement of the ratchet wheel for holding said special pawl either in or out of engagement with said wheel.
5. 7. The combination with a ratchet wheel, and a driving pawl therefor, of a special pawl, a locking device for holding said special pawl either in or out of engagement with said wheel, and means for controlling the operation of the locking device by the movement of the driving pawl.
10. 8. The combination with a ratchet wheel having one tooth removed, a driving pawl, and a holding pawl, of a special pawl for enabling the driving pawl to move the toothless part of the ratchet wheel past the holding pawl, and means controlled by the movement of the driving pawl.
15. 15. for controlling the engagement or non-engagement of said special pawl.
9. The combination with a ratchet wheel having one tooth removed, a driving pawl, and a holding pawl, of a special pawl for enabling the driving pawl to move the toothless part of the ratchet wheel past the holding pawl, a locking device for holding the special pawl in or out of engagement with the wheel, and means for operating said locking device by the movement of said driving pawl.
20. 10. The combination with a ratchet wheel having one tooth removed, a driving pawl, and a holding pawl, of a special pawl for enabling the driving pawl to move the toothless part of the ratchet wheel past the holding pawl, means for controlling the engagement or non-engagement of said special pawl by the movement of the driving pawl,
25. 30. and a locking device carried by the ratchet wheel and arranged to hold the special pawl in the position determined by the driving pawl.
11. In the switching mechanism of a telephone exchange, the combination with a movable ratchet wheel, of a pawl-locking device carried by said wheel, and a pawl arranged to be held in either of two positions by said locking device.
30. 12. In the switching mechanism of a telephone exchange, the combination with a movable ratchet wheel, of a pawl-locking device carried by said wheel and adjustable with respect thereto.
35. 13. The combination with a movable ratchet wheel, of an adjustable pawl-locking device, and means for securing said device at any desired position on said wheel.
40. 14. The combination with a switching mechanism, a magnet for operating it, and an electric circuit by which impulses may be sent through said magnet, of a condenser located in a normally open bridge between the branches of said circuit, and means by which said bridge is temporarily closed once during each forward movement of said switching mechanism.
45. 15. The combination with a switching mechanism, and a propelling magnet therefor, of a circuit for operating said magnet, and means associated with said circuit for neutralizing the residual magnetism of said magnet at the termination of each operation thereof.
50. 16. The combination with a ratchet wheel, a magnet for advancing it, and a spring for returning it to normal position when released, of a telephonic connection closed by the compression of the retractile spring on the advance of the wheel and broken by the return of said wheel to its normal position.
55. 17. The combination with a ratchet wheel, and means for advancing it, of two contact springs provided with connections to said wheel for returning it to normal position when released, and telephonic connections closed by the compression of said springs upon the advance of said wheel.
60. 18. The combination with a ratchet wheel, and means for advancing it, of contact springs closed by the forward movement of said wheel, automatic means for normally stopping said wheel before said springs are closed, and special means for causing said wheel to move beyond its normal stopping point.
65. 19. The combination with a series of ratchet wheels, magnets for simultaneously advancing them, and automatically operating means for normally stopping said wheels at a predetermined point in their advance, of means for moving selected wheels beyond their normal stopping points, and means whereby the magnets used for advancing the wheels serve also for selecting desired wheels for further advance.
70. 20. The combination with a party line consisting of two conductors leading to a series of local stations, of a switching mechanism at each station permanently connected in bridge of said conductors, a telephone receiver at each station normally connected in bridge of said conductors, circuit making and breaking devices in said last named bridges and located on each side of said receivers, means by which upon operating said switching mechanism by impulses sent over said line the last named bridges will be broken on both sides of said receivers, and means by which upon advancing the switching mechanisms beyond a predetermined point the bridges for said receivers will be again closed.
75. 21. The combination with a party line consisting of two conductors leading to a series of local stations, of a switching mechanism at each station, a telephone receiver at each station normally connected in a closed bridge of said conductors, means by which upon operating said switching mechanisms said bridges will be opened on both sides of the receivers, and means by which upon any of said switching mechanisms being advanced beyond a predetermined point the bridges at such stations will be closed on both sides of the receivers thereat.
80. 22. The combination with a series of stations normally in telephonic connection with a party line, a switching mechanism at each station and means controlled from a central office for operating said switching mechanisms to simultaneously break all telephonic connections and subsequently to reestablish the telephonic connections of selected stations, of emergency devices at each station so arranged that an unselected station may signal the central office while two selected stations are in telephonic connection with each other, and means by which such emergency devices are inoperative until the selective operation is completed.
85. Signed at Chicago, Ill., this 18th day of August 1905.
